UNITED STATES PATENT OFFICE

EDWARD WEST ARMSTRONG, OF BELFAST, NORTHERN IRELAND

SEWING MACHINE

Application filed May 16, 1928, Serial No. 278,115, and in Great Britain February 6, 1928.

This invention relates to embroidery sewing machines, and has particular reference to machines of this type in which a needle bar is operatively carried by a head adapted to be swung to and fro in a fixed frame by a pitman or equivalent.

According to the present invention, I provide a multiple needle embroidery sewing machine with means whereby the needles are 10 vibrated so that they move relatively to each other in opposite directions. Preferably, the said means comprises an adjustment device whereby the amplitude of the vibrations of one of two needles is variable independently 15 of the amplitude of the vibrations of the other needle. The said means may also comprise supports for the needles wherein the needles are relatively adjustable so as to pass each other during their vibrations.

20 One embodiment of the invention, as applied to a two-needle embroidery sewing machine, will now be described, by way of example, with reference to the annexed drawings, in which:—

25 Fig. 1 is a front view of the said embodiment, with adjacent parts of the sewing machine;

Fig. 2 is a front view, similar to that in Fig. 1 but with the operating parts in different position;

30 Figs. 3, 4 and 5 are plan, front and side views of the right-hand needle holder (Figs. 1 and 2);

35 Figs. 6, 7 and 8 are plan, front and side views of the left-hand needle holder (Figs. 1 and 2);

Fig. 9 is a view of the two needles face to face, as they appear from the front of the sewing machine;

40 Fig. 10 is a view of one needle looking towards the face thereof;

Fig. 11 is a view of the right-hand needle (Fig. 1) looking from the rear;

45 Figs. 12 and 13 are views showing diagrammatically two embroidery designs carried out according to the invention;

Fig. 14 is a rear view of the arrangement shown in Fig. 1;

50 Fig. 15 is a side view partly in section of the said arrangement (Fig. 1).

Referring to the drawings:—

The needle bar 1 of the sewing machine is carried by the usual swinging head 2 which is suspended in the fixed frame 3 of the machine and vibrated relatively thereto by the 55 usual vibrating pitman 4. The pitman 4 may be reciprocated by any of the known means for such purpose, one means being indicated diagrammatically at A in Fig. 1.

The bottom of the needle bar 1 is bifurcated and between the bifurcated ends of the said bar, the tongue 5 of a carrier 6 is engaged, being held rigidly therein by a pin 5^a. The top of the tongue 5 is also bifurcated, the bifurcated ends thereof projecting 65 up the side of the needle bar 1 and thereby ensuring firm connection between the bar 1 and the carrier 6.

As will be seen from Figs. 1 and 2, the carrier 6 is of T shape, the horizontal portion of the carrier being formed with a slot 7. Two needle holders 8 and 9 are mounted in the carrier 6, the right-hand needle holder 9 being fixed in the carrier and the left-hand holder 8 being supported slidably therein, as more fully described hereinafter with reference to Figs. 14 and 15. In the adjacent side portions of the needle holders 8, 9 a vertical groove 8^a and 9^a respectively (see Figs. 3 to 8) is formed, and a saw-cut or recess 8^b 70 and 9^b respectively projects inwards from each groove through the bottom portion of the respective holder 8 or 9. By this means, the needles 10, 11 placed in the grooves 8^a, 9^a, 75 are firmly secured or held by tightening up screws 12 which draw the cut or recessed parts of the holders 8, 9 together.

Each of the needles 10, 11 is formed with a flat face 13 (see Fig. 9) and the needles are secured in their holders 8, 9 with the said 80 faces 13 directed towards each other, so that the needle points can be moved very close together before the needle stems touch or meet. Each of the needles 10, 11 is also formed at its opposite sides with a long 85 groove and a short groove respectively as shown in Figs. 9 and 11.

The movable needle holder 8 has formed thereon an angle projection 14 adapted to embrace slidably a depending rod 15. The top 100

end of the rod 15 fits into a vertical recess in a block 17 of dove-tail section (see Fig. 15) and is secured to the said block by a screw 16. The block 17 is slidable in the slot 18 of a bracket 19, which is formed with an upward extension 20 so that it may be secured by a screw pin 21 to a cover plate 22 on the fixed frame 3. The slidable block 17 is also provided with a forwardly projecting stud 23, to which is connected a two-part adjustable pitman 24, the said pitman being retained on the stud 23 by a washer and wing nut 25. The outer end of the pitman 24 is pivotally connected to a lever 26 adapted to be rocked about a fulcrum pin 27 by a bracket 28 secured to the swinging head 2. The fulcrum pin 27 is supported by a slotted bracket 29 attached to the cover plate 22 of the fixed frame 3, and is adjustable upwards or downwards in the slots of the bracket 29 and rocking lever 26 on loosening a nut 30 (see Fig. 15). It will be apparent from the drawing that the adjustment of the fulcrum pin 27 effects a variation in the throw of the pitman 24 and consequently of the rod 15 and needle holder 8.

As will be seen from Figs. 14 and 15, the needle holder 8 is connected to a block comprising a rectangular boss 31 and back-plate 32. The construction of the said block is such that, when connected to the holder 8 about the carrier 6, the boss 31 enters the slot 7 of the carrier, whilst loose movement of the block and needle holder 8 as a whole in a direction at right angles to their direction of sliding is prevented by the back plate 32 and inner surface of the said needle holder 8 gripping slidably the side surfaces of the parts of the carrier 6 above and below the slot 7.

In contrast to the slidable attachment of the needle holder 8, the needle holder 9 is adapted to be fixed in the carrier 6, so that the needle 11 clamped in the said holder 9 is vibrated directly in accordance with the vibrations of the needle bar 1. As shown in Fig. 5, the holder 9 is connected by a bolt 35 to a flanged collar 34, the construction of the said collar being such that, when connected to the holder 9 about the carrier 6, the reduced portion of the collar enters the slot 7 of the carrier, whilst the collar 34 and holder 9 as a whole are drawn together so as to grip the parts of the carrier above and below the slot 7 by means of the bolt 35. As will be understood, adjustment of the needle holder 9 in carrier 6 can be effected on loosening the tightening bolt 35.

When the sewing machine is put into action, the needle 11 operates in known manner, being carried by the holder 9 and carrier 6 fixed to the ordinary needle bar 1. The needle 10, on the other hand, is raised and lowered in conjunction with the needle 11, but, by reason of the above described mechanism,

is caused to vibrate so that the two needles 10, 11 move relatively to each other in opposite directions. The amplitude of the vibrations transmitted to the needle 11 by the ordinary pitman 4 is varied by use of any of the adjustable mechanisms heretofore known in the art for controlling the throw of the said pitman, which means is hereinbelow described. As will be understood, variations so effected in the vibration of the needle 11 are also produced in the same degree in the vibrations of the needle 10. By adjustment of the fulcrum pin 27, however, variations are effected in the amplitude of the vibrations of needle 10, which are independent of the aforesaid variations resulting from adjustment of the control means of the usual pitman 4. For example, by raising the fulcrum pin 27 above the middle position between the bracket 28 and auxiliary pitman 24, the throw of the said auxiliary pitman is made smaller, whereas, by lowering the said pin 27 below the said middle position the throw of the said auxiliary pitman is increased with corresponding variations in the throw of the needle 10 independent of the throw of needle 11.

Furthermore, the needle 11 and the operating mechanism hereinbefore described may be so adjusted that the two needle 10, 11 instead of merely approaching close to one another, actually pass each other during their relative movements. This result is obtained in the manner indicated in Fig. 2, where the needle holder 9 is shown in dotted line tilted about its supporting bolt 35, so that the needles 10, 11, at the inner part of their throws, cross one another. To permit the crossing movement, the grooves 8^a, 8^b, of the needle holders 8 and 9 are made so that when the said holders are arranged on the bracket 19, the needles 10 and 11 are out of alignment, that is, they vibrate not in the same plane but in parallel planes sufficiently spaced apart to prevent interference of the needles 10, 11 with each other. As will be understood, when the needle holder 9 has been turned to the desired angle, the bolt 35 is tightened up so that the said needle holder does not shift when in operation.

By providing an embroidery machine with the needles adapted to be vibrated relatively to each other and with the vibrations under control as aforesaid, it is possible to obtain effects in machine embroidery sewing which greatly enhance the appearance and value of the embroidery, whilst effecting a great saving in time and cost. Two color work can be done on the two-needle machine operated as described so as to produce very attractive designs and combinations of colors. For example, the operating mechanism may be adjusted so as to produce the designs shown in Fig. 12, in which the thread 36 embroidered on the fabric by the one needle may be of different color from the thread 37 embroidered

by the other needle, and the same applies to the threads 38, 39. Moreover, by means of the invention, two halves of a leaf or like design can be done in different colors at one 5 operation, or a split leaf can be done in a single color by the two needles at one operation. One example of work of this kind is shown in Fig. 13, where the threads 40, 41 are sewn simultaneously by the two different needles in 10 respect of each leaf of the design.

It will be apparent that whilst the invention has been described with reference to a two-needle machine, it may be applied to multiple needle machines with three, four or 15 more needles. For example, where four needles are provided, they may be arranged in pairs, and by providing two hooks instead of one for the under thread, each pair of the said needles can be operated in substantially the 20 same manner as described above with respect to the two single needles.

I claim:—

1. In an embroidery sewing machine, the combination of a fixed frame, a swinging 25 head, a needle bar operatively carried by the said head, and means whereby said head is vibrated laterally with a pair of needles, supports therefor, means for securing one of said needle supports in fixed position relatively to 30 said needle bar, means whereby the other of said supports is carried slidably relatively to said bar, a rocking member, a fulcrum for said member on said frame, means connecting one end of said member to said swinging 35 head, and means connecting the other end of said member to said slidable needle support so as to cause said support to vibrate laterally.

2. In an embroidery sewing machine, the combination of a fixed frame, a swinging head, 40 a needle bar operatively carried by the said head, and means whereby said head is vibrated laterally, with a pair of needles, supports therefor, means for securing one of said needle supports in fixed position relatively to 45 said needle bar, means whereby the other of said supports is carried so as to be slidable laterally of said bar, a rocking member, a fulcrum for said member on said frame, means connecting one end of said member to 50 said swinging head, a vertical guide member for said slidable support, means for supporting said guide member so as to permit lateral movement thereof, means retaining said guide member and slidable needle support in 55 vertically slidable connection, and means connecting said guide member to the end of said rocking lever remote from its connection to said swinging head.

3. In an embroidery sewing machine, the combination of a fixed frame, a swinging head, a needle bar operatively carried by the said head, and means whereby said head is vibrated laterally, with a pair of needles, supports therefor, means for securing one 60 of said needle supports in fixed position

relatively to said needle bar, means whereby the other of said supports is carried so as to be slidable laterally of said bar, a rocking member, a fulcrum for said member on said frame, means connecting one end of said rocking member to said swinging head, a laterally-slotted bracket on said fixed frame, a block slidably mounted in said bracket, a vertical guide rod, means whereby said rod is fixed to said slidable block, means 70 on said slidable needle support for embracing said guide rod, and a pitman connecting said slidable block to the end of said rocking lever remote from its connection to said swinging head. 75

4. In an embroidery sewing machine, the combination of a fixed frame, a swinging head, a needle bar operatively carried by the said head, and means whereby said head is vibrated laterally, with a pair of needles, supports therefor, means for securing one of said needle supports in fixed position relatively to 80 said needle bar, means whereby the other of said supports is carried so as to be slidable laterally of said bar, a rocking member, a fulcrum for said member on said frame, means connecting one end of said member to 85 said swinging head, a vertical guide member for said slidable needle support, means for supporting said guide member so as to permit lateral movement thereof, means retaining said guide member and slidable needle support in 90 vertically slidable connection, means connecting said guide member to the end of said rocking lever remote from its connection to said swinging head, means for simultaneously effecting similar adjustments 95 in the amplitudes of the vibrations of the two needles, and means for varying the amplitude of the vibrations of one needle independently of the amplitude of the vibrations of the other needle. 100

5. In an embroidery sewing machine, the combination of a fixed frame, a swinging head, a needle bar operatively carried by the said head, and means whereby said head is vibrated laterally, with a pair of needles, clamp supports therefor, means for securing one of said supports in fixed position relatively to 110 said needle bar, means whereby the other of said supports is carried so as to be slidable laterally of said bar, a slotted rocking lever, a vertically-slotted bracket on said fixed frame, a fulcrum pin carrying said rocking lever, means for adjustably securing said pin in said slotted bracket, means connecting the upper end of said lever to said swinging head, a vertical guide member for 115 said slidable needle support, means for supporting said guide member so as to permit lateral movement thereof, means retaining said guide member and slidable needle support in 120 vertically slidable connection, and means connecting said guide member to the lower end of said rocking lever. 125

6. In an embroidery sewing machine, the combination of a fixed frame, a swinging head, a needle bar operatively carried by the said head, and means whereby said head is vibrated laterally, with a pair of needles, clamp supports therefor, means for securing one of said supports in fixed position relatively to said needle bar, means whereby the other of said supports is carried so as to be slidable laterally of said bar, a slotted rocking lever, a vertically-slotted bracket on said fixed frame, a fulcrum pin carrying said rocking lever, means for adjustably securing said pin in said slotted bracket, means connecting the upper end of said lever to said swinging head, a laterally-slotted bracket on said fixed frame, a block slidably mounted in said last mentioned bracket, a vertical guide rod, means whereby said rod is fixed to said slidable block, means on said slidable needle support for embracing said guide rod, and a pitman connecting said slidable block to the lower end of said rocking lever.

7. In an embroidery sewing machine, the combination of a fixed frame, a swinging head, a needle bar operatively carried by the said head, and means whereby said head is vibrated laterally, with a pair of needles, supports therefor, a carrier slotted laterally of said bar, means for securing said carrier to said bar, means for securing one of said needle supports in angularly adjustable position relatively to said needle bar, means whereby the other of said supports is carried slidably relatively to said bar, and means whereby said last mentioned support is vibrated laterally so that said needles move relatively to each other in opposite directions.

In testimony whereof I affix my signature.

40 EDWARD WEST ARMSTRONG.
